UNITED STATES PATENT OFFICE

CARLOS SCHMITTHENNER, OF HEIDENHEIM-ON-THE-BRENZ, GERMANY

SAFETY DEVICE FOR WING TYPE TURBINES, PUMPS AND SIMILAR PIECES OF APPARATUS WITH MOVABLE VANES

Application filed February 9, 1931, Serial No. 514,380, and in Germany February 20, 1930.

The following invention consists of a safety device for wing type turbines, pumps, and similar pieces of apparatus with movable vanes, and is concerned with the prevention of entry of water into the runner head.

In wing type turbines, pumps, and similar apparatus with movable vanes the runner head is filled with oil. In order to prevent the entry into the oil space in the hub of water which flows past, and which is also under pressure, packing devices are inserted at the flanges of the runner blades. Should the water pressure on the outside be noticeably higher than that of the oil on the inside, then it is impossible to prevent even the best packing devices from gradually allowing water to enter the oil. This entry of water is exceptionally serious, since the trunnions and links of the governing mechanism for the runner blades would soon fail due to poor lubrication.

The following invention is designed to overcome this disadvantage. In my companion patent application Serial No. 514,379, filed February 9, 1931, means were given to increase the pressure of oil, whereas here it is proposed to conduct the water which enters at the high pressure side of the head in the clearance between the blade and head, to the low pressure side of the head to escape through an enlarged clearance between the blade and head. By the high pressure side, I of course mean the incoming side of the operating water under pressure from the waterhead as received by the blade, while by the lower pressure side, I mean the discharge side of the blade where the operating water after doing its work is delivered into the tailwater in the partial vacuum of the usual draft-tube. During service with wing type turbines, pumps and similar pieces of apparatus, there is on the side on which the operating water reaches the runner blades a certain pressure which depends on the height of the head water level, whereas on that side from which the operating water discharges there is a certain low pressure, which depends on the position of the tail water level. This fact is used to prevent the entry of water into the oil space in the runner head,

due to the effect of the pressure operating on the incoming side. For this purpose in the annular clearance between the vane flanges and the runner hub there are arranged ring grooves in which pressure equalizing can take place around the flanges. This equalizing of pressure can also with advantage be improved when the clearance between the vane flanges and the runner hub is made narrower on the intake side, and broadens on the discharge side.

In the drawing is shewn schematically an example of the arrangement of the device, and Figure 1 is an axial section through the runner trunnions in the runner hub, while Figure 2 is an end view of a runner vane. In the bearing of the runner head 1, are fitted pins 2, belonging to the runner blade 3, these pins being placed in double bearings and arranged to turn. The interior space 4, between the bearings is filled with oil for lubricating all trunnions and links. Between flange 5 of the blade 3 and the runner head 1 is inserted packing 6.

The exterior circumference of the runner flange 5 moves with a very small clearance on a suitable boss on the runner head 1, so that the water can only pass through a narrow clearance 7. Clearance 7, which in the upper part of the runner blade is very narrow, and at the lower part is noticeably increased, is broken by a circular groove 8.

The operation of the device is as follows:— During service with turbines, pumps, or similar pieces of apparatus, due to the high pressure on the approach side of the runner blade, there is a certain amount of water passed through clearance 7 into annular space 8, and flows thence to the lower side. Since now however, on the discharge side there is considerably less pressure, and in certain cases there is even a vacuum existing,—and also due to the fact that the ring clearance 7 is considerably wider, there is ample opportunity for discharge into the tail race of the water that has entered annular channel 8.

By suitably dimensioning the annular space and making the increase on the discharge side of ample proportions, it can be so arranged that only a small pressure exists

throughout the whole of the annular space. So small a pressure in fact, that the entry of water into the oil filled runner head is made impossible. The exact form of the water discharge grooves need not here be considered, and it is also immaterial whether one or more grooves are arranged one behind the other. Depending on the space available, these grooves can either only be inserted in the runner head boring or only in the blade flange, or even in both parts of the equipment. It is a matter of indifference whether the clearance is cylindrical or conical.

15 I claim:

1. In a blade type turbine, a vertical axis runner head having a bearing and a seat, a blade having a pin and a flange fitting respectively in said bearing and seat for rotary adjustment of the blade, means for preventing outside water from entering the bearing, comprising an annular drain channel in the joint between the seat and flange, adapted to receive the water entering the joint at the high pressure side of the head and to conduct the received water to the low pressure side of the head, and a water outlet to the outside of the head, extending from said drain channel at the low pressure side of the head.

2. A blade type turbine comprising, with a vertical axis runner head having a bearing and a seat therein, and a blade having a pin and a flange fitting respectively in said bearing and seat, means for preventing outside water from entering the bearing through the joint between the seat and flange, comprising an annular drain channel cut in part in the seat and in part in the flange to receive the water entering the joint at the high pressure side of the head, said channel adapted to convey the received water to the low pressure side of the head, and a water outlet to the outside of the head, extending from said drain channel at the low pressure side of the head.

3. In a blade type turbine, a vertical axis runner head having a bearing and a seat, a blade having a pin and a flange fitting respectively in said bearing and seat for rotary adjustment of the blade, the joint clearance between the seat and flange at the high pressure side of the head being relatively small while that at the low pressure side thereof is relatively large to provide a water outlet, and a drain channel following the joint between the seat and flange, extending from the relatively small joint clearance to the relatively large joint clearance, whereby water entering the high pressure side of the head will be conducted for discharge at the low pressure side thereof.

In testimony whereof I affix my signature.
CARLOS SCHMITTHENNER.
